D. GREEFS

CLASP OR BUCKLE

Filed Nov. 23, 1923

INVENTOR:
Daniel Greefs,
BY
Fraentzel and Richards
ATTORNEYS

UNITED STATES PATENT OFFICE.

DANIEL GREEFS, OF IRVINGTON, NEW JERSEY, ASSIGNOR TO THE BRASSLER CO., A CORPORATION OF NEW JERSEY.

CLASP OR BUCKLE.

Application filed November 23, 1923. Serial No. 676,485.

To all whom it may concern:

Be it known that I, DANIEL GREEFS, a citizen of the United States, residing at Irvington, in the county of Essex and State 5 of New Jersey, have invented certain new and useful Improvements in Clasps or Buckles; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification.

15 This invention relates, generally, to improvements in clasps or buckles; and, the present invention has reference, more particularly, to a novel and simply constructed, as well as an ornamental device, in the form 20 of a clasp or a buckle, which is especially adapted for use with the usual ribbons, such as are employed with wrist-watches, but which may also be used in other various manners.

25 The present invention has for its principal object to provide a clasp or buckle, comprising a pair of separable clasp or buckle-members, with one of which an end-portion of a ribbon, or the like, is adapted to be connected, the other clasp or buckle-member being slidably and adjustably mounted upon another portion of the ribbon, or the like, and the two clasp or buckle-members being 30 adapted to be snapped into retaining engagement with one another, for maintaining the ribbon in its position about the wrist, when used in connection with a wrist-watch, or the like, or when employed as a buckle, in connection with a belt, for 35 maintaining the belt in its position about the body of the wearer.

40 Other objects of the present invention not at this time more particularly enumerated will be clearly understood from the following detailed description of the present invention.

45 With the various objects of the present invention in view, the said invention consists, primarily, in the novel clasp or buckle hereinafter set forth; and, the said invention consists, furthermore, in the novel arrangements and combinations of the various devices and parts, as well as in the details of the construction of the said parts, 50 all of which will be more fully described in

the following specification, and then finally embodied in the clauses of the claims, which are appended to and which form an essential part of the said specification.

The invention is illustrated in the accompanying drawings, in which:—

Figure 1 is a front face view of a clasp or buckle, made according to and embodying the principles of the present invention, showing one of its uses in connection with a ribbon, 65 adapted to be arranged about the wrist of a person; and Figure 2 is a view of the reverse side of the clasp or buckle and the ribbon shown in said Figure 1.

Figure 3 represents face views, showing 70 collectively, the separated members of the clasp or buckle, illustrating more particularly one manner of attaching the ornamental face-plate of the clasp or buckle to an end-portion of the ribbon, and also showing 75 the slideable and adjustable arrangement of the back-plate of the clasp or buckle upon another portion of the ribbon.

Figure 4 is a vertical sectional representation of the clasp or buckle and the ribbon, 80 said section being represented as being taken on line 4—4 in said Figure 1.

Figure 5 is a rear face view of the back-plate of the clasp or buckle, showing in connection with said plate, one arrangement of 85 a post or stud-engaging spring; and Figure 6 is a perspective view of the spring shown in said Figure 5 in connection with the said back-plate.

Similar characters of reference are 90 employed in all of the said above described views, to indicate corresponding parts.

Referring now to the said figures of the drawings, the reference-character 1 indicates the complete clasp or buckle for use 95 with a ribbon 2, or the like, in a manner to be presently set forth.

The clasp or buckle comprises an ornamental face-plate, as 3, which is preferably outwardly convexed, substantially as indicated in Figure 4 of the drawings, the said plate being provided at one edge with an extension 4, forming with said edge of the face-plate, a laterally extending slot or opening, as 5. As shown in said Figure 4, 105 an end-portion, as 6, of the ribbon 2, is passed into and through the slot or opening 5, forming a loop 7 about the said extension or bar 4, the looped portions of the ribbon being suitably secured together by sew- 110

ing, or otherwise. Projecting rearwardly from the back of the face-plate 3 is a laterally extending spring-engaging member or rib, the outer and enlarged edge-portion 8 of which is suitably connected with said back of the face-plate by means of a restricted portion 9, substantially as shown in said Figure 4, and for the purpose to be presently more fully described.

10 The reference-character 10 indicates the back-plate of the clasp or buckle, the said plate being also preferably outwardly convexed, as shown, the said plate at its upper and lower edges being preferably bounded by rearwardly extending wall-members or ribs 11 and 12, provided with inwardly projecting retaining lugs or ears 13 and 14. At its laterally extending marginal edges, the said back-plate is provided with other rearwardly projecting and laterally extending members or bars, as 15 and 16, said members or bars providing with said laterally extending marginal edges of the back-plate, suitable laterally extending receiving openings or slots, as 17 and 18. The said back-plate is also formed with a laterally extending opening or slot 19, of such width that the enlarged portion 8 of the spring-engaging member or rib of the face-plate may 20 readily enter the said opening or slot 19, for snapped engagement with the bowed portions 21 and 22 of a spring 20, of the general configuration shown in Figures 5 and 6 of the drawings. At its ends 23 and 24 this spring is secured and held against the rear face of the back-plate by means of the previously mentioned retaining lugs or ears 13, as indicated in said Figure 5, the bowed portions 21 and 22, lying directly back of 30 the opening or slot 19, so as to be in the path of the enlarged portion 8 of the spring-engaging member or rib of the face-plate, so that said enlarged portion 8 can be forced over, and the restricted portion 9 readily 40 snapped into holding engagement with the bowed portions 21 and 22 for maintaining a locked or retained engagement of the face-plate with the back-plate, and permitting the parts to be readily separated, if desired, 45 and as will be clearly evident.

50 Referring to Figure 4 of the drawings, it will be seen that the said back-plate is slidably and adjustably mounted upon the ribbon, by having the end-portion 25 of the ribbon passed over the bar 15 into and through the opening or slot 17, and back of the said back-plate, then into and through the opening or slot 18 and over the bar 16, whereby the back-plate is held by frictional 55 engagement with the ribbon, against movement thereon, as will be clearly evident.

60 Such adjustment having been made, it will be readily understood, that the face-plate of the clasp or buckle can be easily 65 snapped into its holding relation with and

over the back-plate, and can just as readily and easily be separated therefrom, when necessary.

While in the foregoing description of the invention I have described my novel form 70 of clasp or buckle in connection with a ribbon, such as is used with wrist-watches, I am fully aware that the device may be made of such size that is readily applicable as a belt-buckle; and also, that my invention 75 may be put to other uses, as in clasps for garters, and the like.

I am also aware, that changes may be made in the general arrangements and combinations of the various devices and parts, 80 as well as in the details of the construction of the same, without departing from the scope of the present invention as set forth in the foregoing specification, and as defined in the clauses of the claims which are 85 appended thereto. Hence, I do not limit my present invention to the exact arrangements and combinations of the various devices and parts, as described in the said specification, nor do I confine myself to the 90 exact details of the construction of the said parts, as illustrated in the accompanying drawings.

I claim:

1. A clasp or buckle comprising a face-plate provided at one edge with means for attachment thereto of an end-portion of a ribbon, belt, or the like, a spring-engaging lug extending laterally across a portion of the rear face of said face-plate and also projecting rearwardly from said plate, said lug having an enlarged marginal portion and a restricted portion between said enlarged portion and the rear face of the plate, combined with a back-plate, provided with marginal bars and laterally extending slots for adjustably mounting the back-plate upon another portion of the ribbon, belt, or the like, the said back-plate being provided with a laterally extending opening for reception of said spring-engaging lug, retaining lugs extending rearwardly from the longitudinally extending edges of the back-plate, and a spring between said lugs and held by said lugs upon the back of said back-plate, said spring having bowed portions lying directly back of said opening with which the restricted portion of the spring-engaging lug is adapted to be brought into separable holding engagement.

2. A clasp or buckle comprising a face-plate provided at one of its laterally extending edges with a marginal bar and a laterally extending slot for attachment thereto of an end-portion of a ribbon, belt, or the like, a spring-engaging lug extending laterally across a portion of the rear face of said face-plate and projecting rearwardly from said plate, said lug having an enlarged marginal portion and a restricted 120

- portion between said enlarged portion and the rear face of the plate, combined with a back-plate, means connected with said back-plate for adjustably mounting the same upon another portion of the ribbon, belt, or the like, the said back-plate being provided with a laterally extending opening for reception of said spring-engaging lug, and a spring mounted upon the back of said back-plate, said spring having bowed portions lying directly back of said opening with which the restricted portion of the spring-engaging lug is adapted to be brought into separable holding engagement.
- 15 3. A clasp or buckle comprising a face-plate provided at one of its laterally extending edges with a marginal bar and a laterally extending slot for attachment thereto of an end-portion of a ribbon, or the like, a spring-engaging lug extending laterally across a portion of the rear face of said face-plate and projecting rearwardly from said plate, said lug having an enlarged marginal portion and a restricted portion
- 20 25 between said enlarged portion and the rear face of the plate, combined with a back-plate, provided with marginal bars and laterally extending slots for adjustably mounting the back-plate upon another portion of the ribbon, belt, or the like, the said back-plate being provided with a laterally extending opening for reception of said spring-engaging lugs, retaining lugs extending rearwardly from the longitudinally extending edges of the back-plate, and a spring between said lugs and held by said lugs upon the back of said back-plate, said spring having bowed portions lying directly back of said opening with which the restricted portion of the spring-engaging lug is adapted to be brought into separable holding engagement.

In testimony that I claim the invention set forth above I have hereunto set my hand this 21st day of November, 1923.

DANIEL GREEFS.
